UNITED STATES PATENT OFFICE.

PETER C. BURNS, OF CHICAGO, ILLINOIS.

DESIGN FOR A HORN.

43,416.

Specification for Design.

Patented Jan. 7, 1913.

Application filed October 29, 1912. Serial No. 728,507. Term of patent 7 years.

To all whom it may concern:

Be it known that I, PETER C. BURNS, a citizen of the United States, residing at Chicago, county of Cook, and State of Illinois, have invented a new, original, and ornamental Design for a Horn, of which the following is a specification, reference being had to the accompanying drawing, forming a part thereof.

Figure 1 of the drawing is a side eleva-

tion, and Fig. 2 is an end elevation of a horn showing my new design.

I claim:

The ornamental design for a horn as shown.

PETER C. BURNS.
